UNITED STATES PATENT OFFICE

2,546,696

COMB

Peter L. Mater, Leominster, Mass.

Application December 22, 1948, Serial No. 66,718

3 Claims. (Cl. 132—18)

1

This invention relates to new and improved combs and more specifically to those which are particularly adapted for cleaning the hair and for removing dust, dandruff, etc. therefrom.

The principal object of the invention resides in the provision of a double comb, i. e., one having two separable parts with similar complementary teeth which are constructed to provide conjoining recesses on the side surfaces thereof, such recesses receiving dust, dandruff, etc. from the hair as the comb is drawn through the same and the recesses receiving the material both from a mechanical scraping action and by reason of the attraction of static electricity of the comb as it is drawn through the hair, said attraction acting on loose particles therein to attract the same into the recesses.

Further objects of the invention reside in the provision of a comb as above described and in a particular new and useful manner of securing the combs together for use in combination, said means also providing for quick and easy separation of the two parts of the comb for cleaning.

Other objects and advantages of the invention will appear hereinafter.

Reference is to be had to the accompanying drawings in which

Fig. 1 is a view in elevation of a comb according to the present invention, part being broken away and in section;

Fig. 2 is an enlarged section on line 2—2 of Fig. 2;

Fig. 3 is a fragmentary view similar to Fig. 1, parts being broken away and showing the comb locking means in unlocked condition;

Fig. 4 is an enlarged section on line 4—4 of Fig. 2;

Figs. 5, 6, 7 and 8 are sections similar to Fig. 4 but showing modifications of the tooth structure;

Fig. 9 is an end view of the comb showing the locking means therefor, part being broken away, and

Fig. 10 is a section similar to Fig. 2 showing a modification, part being removed.

The present invention provides three main parts, two of which are complementary comb sections generally indicated at 10 and 12 and the third one being a locking means therefor, generally indicated at 14.

The part 14 is elongated and U-shaped in cross section, as clearly shown in Fig. 2, and it is provided with a pivot pin or the like 16 by which it is pivoted to the comb section 10. However, at the end thereof adjacent the pivot pin 16 the

2

U-shaped locking means 14 is solid, as indicated at 18 and the entire locking device 14 is pivotable from the locked condition of Fig. 1 to the unlocked condition of Fig. 3. In Fig. 1, the U-shaped locking device 14 snaps down over the backs of both of the combs, holding them together by conventional snap means indicated at 20. These snap means comprise small protuberances and corresponding dents, so that the two comb parts 10 snap into mutually latched relation.

The comb section 12 is cut out as at 22 to accommodate the solid portion 18 of the locking device 14.

The separate teeth 24 and 26 of the sections 12 and 10, respectively, are similar but reversed, as shown in Fig. 4, and at their lateral edges are provided with cut away portions 28 which together form dust and dandruff collecting pockets or receptacles. The line 30 indicates the dividing line 20 between the two combs and when the same are separated, they open on the line 30 providing for extremely quick and easy cleaning of the detritus receiving pockets or receptacles, which will be seen not to have any inaccessible or hard to get at portions but to be located on bevels as indicated at 28, so that the cleaning section may be extremely simple and quick, as for instance, merely by rinsing.

Figs. 5, 6, 7 and 8 also show outlines of teeth which may be used and it is to be understood that although this showing is illustrative, it is not conclusive and any other similar formations useful to the purpose come within the limits of the invention.

For instance, in Fig. 5, the teeth 32 are cut away from their outer edges 34; in Fig. 8 the recesses are formed by symmetrical concavities 36. However, in all cases the dividing line 30 is shown centrally of the combined teeth and the reduced portions of the teeth conjoin to form the pockets for receiving the dandruff, etc.

It will be seen that this invention provides a very easily cleaned comb for quickly and easily cleaning dust, dandruff and the like from the hair; and the comb appears very similar to any ordinary comb but in reality is considerably different and is easily taken apart and put back together again for the indicated usage.

Fig. 10 shows a modification wherein the teeth 40 and 42 appear just like those at 24 in Fig. 1, but from the edges they are cut all the way through at the contacting edges equivalent to the edges at 30, leaving thin spaced teeth 44, 46 which meet at 48 and leave a relatively large detritus hole or receptacle 50 therebetween.

Having thus described my invention and the advantages thereof, I do not wish to be limited to the details herein disclosed otherwise than as set forth in the claims, but what I claim is:

1. A comb comprising a pair of solid toothed comb parts, means temporarily securing the comb parts together with the teeth of each part flatly and solidly contacting corresponding teeth of the other part to form single solid combined operating teeth, and each tooth being reduced in thickness adjacent the line of contact with the corresponding tooth thereof, forming combined lateral recesses at side surfaces of the combined teeth.

2. A dandruff comb comprising a pair of solid separable toothed comb parts, arranged in side by side relation with the teeth of each comb part flatly and solidly contacting the corresponding teeth of the other comb part, each tooth having a reduced portion substantially the length thereof at the surface contacting the corresponding tooth of the other comb part to form dust and dan-

druff receiving pockets in the combined teeth at the side surfaces thereof.

3. The comb of claim 2 including means to lock the comb parts together said means comprising a U-shaped elongated element pivoted to one comb part and pivotable to receive the backs of both comb parts within the U.
